UNITED STATES PATENT OFFICE.

CHARLES E. CARPENTER, OF MINNEAPOLIS, MINNESOTA, ASSIGNOR TO THE CARPENTER-NEVENS ELECTRO-HEATING COMPANY, OF SAME PLACE.

ELECTRIC SOLDERING-IRON.

SPECIFICATION forming part of Letters Patent No. 436,119, dated September 9, 1890.

Application filed June 21, 1890. Serial No. 356,200. (No model.)

To all whom it may concern:

Be it known that I, CHARLES E. CARPENTER, a citizen of the United States, and a resident of the city of Minneapolis, in the county 5 of Hennepin and State of Minnesota, have invented certain new and useful Improvements in Electric Soldering-Irons, of which the following is a specification.

This invention relates to improvements in 10 that class of soldering-irons commonly known as "hatchet-irons," principally employed in the making of cans and analogous uses. These irons have the general shape of an ordinary hatchet and derive their heat from an external source, generally by being inserted 15 directly into the fire.

The prime object of this invention is to have 20 such an iron electrically heated and of such construction that the wearing parts thereof may be readily replaced by new parts.

Another object is to have the electro-heating 25 elements of the iron so disposed that the electrical conductor or resistance may at all times be maintained under sufficient pressure 25 to promote the desirable results from its use to the maximum degree.

These objects are attained by the devices 30 illustrated in the accompanying drawings, in which—

35 Figure 1 represents a side elevation of a soldering-iron embodying my invention, with parts broken away to more clearly disclose the internal structure thereof; Fig. 2, a top plan view thereof, shown partly in horizontal section on the line 2 2 of Fig. 1; and Fig. 3, a transverse vertical section on the line 3 3 of Fig. 1.

Similar letters of reference indicate the 40 same parts in the several figures of the drawings.

Referring by letter to the accompanying drawings, A indicates the main body of the iron, preferably composed of a block of copper of suitable dimensions and configuration, 45 on each side of which is located a cheek or compressing plate B, preferably composed of iron, between each of which and the body is interposed a resistance or electrical conductor C, separated from both the body and the 50 cheeks by layers of electrical insulating ma-

terial D E, preferably in the form of thin sheets of asbestos paper, to one which the resistance in the form of a fine iron wire may be suitably secured. This electrical insulation, however, should be of such character as 55 to oppose the minimum obstruction to the passage of heat from the resistance to the body of the iron. The inner insulation D is interposed between the resistance and body of the iron solely for the purpose of preventing 60 electrical contact therebetween and the resultant short-circuiting of the resistance and other evils which would necessarily attend such contact; but the insulation E between the cheeks and the resistance is de- 65 signed to perform the further function of preventing either the conduction or radiation of the heat evolved from the resistance, and should therefore be of such thickness and character as to accomplish this desirable end. 70

The cheeks are secured in position upon the body by means of screws F working freely through one of them and the body and engaging screw-threaded perforations or sockets in the other cheek, thus furnishing at the 75 same time a means for binding the cheeks and the intervening elements against the iron body under pressure, which may be varied at will and which at all times will be sufficient to prevent short-circuiting of the resistance or 80 electrical conductor and the resultant fusion thereof or the falling away of the same from the insulation to which it is secured or between which it is confined.

The body portion of the iron extends slightly 85 below the cheeks, and is provided with a removable blade G, fitting onto the body and provided with a groove of any suitable character fitting closely upon a ridge of corresponding form on the body A, extending from 90 end to end thereof. This ridge-and-groove connection subserves the double purpose of providing a large surface for contact between the body and the blade and of preventing a lateral movement of the blade with relation 95 to the body.

The resistance employed is preferably of the reflex type, as illustrated in Fig. 1, and composed of iron wires disposed upon the card of asbestos board in any suitable manner. 100

For convenience in manipulating the iron I provide a cap H, secured to one end of the body by screws I, into which cap is screwed one end of a tube J, which acts as a handle and also provides a channel for the inleading wires K K to the resistance, the tube at its opposite end having fastened thereon a ferrule L to receive the handle proper M of the tool.

For the better insulation of the handle from the heat of the iron body a packing of asbestos N or other suitable material is interposed between the cap and the body.

From the foregoing it will be readily understood that while in this iron are contained features common to other irons heretofore patented by me at the same time it contains structural differences possessing many advantages in the uses to which my invention is to be put. For instance, the body, which is composed of a flat block of copper or other suitable metal, has a heating-resistance lying on each side thereof and confined thereon in such manner that the heat evolved from the resistances will be confined directly to the body and from it transmitted by conduction to the removable blade, which, being a part subjected to constant wear, may by reason of its construction be readily replaced by a new blade when worn beyond usefulness.

Having described my invention, what I claim and desire to secure by Letters Patent is—

1. In an electric soldering-iron, the combination, with the body and the cheek-plates thereof, of an electrical conductor or resistance interposed between each of said plates and the body, and an insulation interposed between said resistances and the body and the plates, substantially as described.

2. In an electric soldering-iron, the combination, with the body, the cheek-plates on each side thereof, and a removable blade attached

to said body, of an electrical conductor or resistance interposed between each of said plates and the body, and an insulation interposed between each of said resistances and the body and plates, substantially as described. 45

3. In an electric soldering-iron, the combination, with the body, the cheek-plates on each side thereof, and means for binding said plates to the body under pressure, of an electrical conductor or resistance interposed between each of said plates and the body, and an insulation interposed between each of said resistances and the body and plates, substantially 55 as described.

4. In an electric soldering-iron, the combination, with the body, the cheek-plates on each side thereof, means for securing said plates to the body under pressure, and a removable 60 blade attached to the body, of an electrical conductor or resistance interposed between each of said plates and the body, and an insulation interposed between said resistances and the body and plates, substantially as de- 65 scribed.

5. In an electric soldering-iron, the combination, with the body, the cheek-plates, screws securing said plates to the body, a removable blade provided with a longitudinal groove fitting upon a ridge on the body, and a screw passing through the body and securing the blade in position, of an electrical conductor or resistance interposed between each of said plates and the body, and an insulation interposed between said resistances and the body and plates, substantially as described. 70 75

In testimony whereof I affix my signature in presence of two witnesses.

CHARLES E. CARPENTER.
